INVENTOR.
O. W. ECKSTEIN.
BY *Fred J. Taylor*
ATTORNEY.

UNITED STATES PATENT OFFICE

OLIVER W. ECKSTEIN, OF OILFIELD, CALIFORNIA

HATRACK

Application filed September 22, 1928. Serial No. 307,655.

My invention relates to article supporting devices, and more particularly to devices for supporting hats on the top of an automobile.

It accordingly is an object of my invention to provide a novel form of article supporting device in which a loop, preferably formed of wire, is adapted to be anchored to the top of an automobile by means of a pair of anchoring plates, said loop being preferably hinged to a pair of projections extending from said plates, spring means being also provided to engage said projections and the ends of said loop to resist the movement of said loop so that an article such as a hat, may be held between said loop and the top of the automobile.

It is also within the province of my invention to provide my novel form of article supporting device with an adjusting means so that hats or articles of different sizes may be supported.

The above and further objects and advantages of my invention, as will hereinafter more fully appear, I attain by the construction described in the specification and illustrated on the drawings forming a part of my application.

Reference is had to the accompanying drawings, in which similar reference characters denote similar parts. In the drawings,

Fig. 1 is a fragmentary perspective view of an automobile showing one form of my invention in position on the top thereof without the hat,

Fig. 2 is a fragmentary side elevational and part sectional view of Fig. 1, drawn on a somewhat larger scale, but showing the hat in position,

Fig. 3 is a perspective view of my invention removed from the automobile,

Fig. 4 is an enlarged top plan view of a modified form of my invention,

Fig. 5 is a top plan view of Fig. 4,

Fig. 6 is an enlarged cross-sectional view taken on the line 6—6, Fig. 4,

Fig. 7 is a fragmentary enlarged detail view of one of the anchoring plates or devices and spring bearing projections, showing how the springs are associated therewith, and

Fig. 8 is a view taken at right angles to Fig. 7.

Describing my invention more in detail, I preferably associate the device with the top 2 of the automobile 4, said device being anchored to one of the cross-bars 6 of said top, although, of course, said device may be positioned in any other suitable place.

For this purpose, the devices 8 are provided, which devices may be in the form of plates 10, provided with perforations 12 to receive suitable fasteners, whereby said plates may be secured to the cross bar 6, each of said plates being provided with bent over portions 14, which portions are also perforated to receive the projections 16, preferably in the form of a headed bolt, extending outwardly from said portions, and having a kerfed end 18 (Figs. 7 and 8) for receiving and anchoring one end of the spring 20, preferably coiled about said projections, the other end 2 of said springs engaging the ends 22 of the loop 24 adapted to support the hat 26, as seen in Figs. 1 and 2. The ends 22 of the loop 24 are hinged to the projections 16 by means of the looped ends 28 so that when the loop 24 is pulled down against the tension of the springs 20 and the hat 26 inserted therein, said loop will fly back to the position shown in Fig. 2.

To accommodate hats or other articles of different sizes, a cross-bar 30', extending across the loop 24 (Figs. 4 and 6) may be provided, the ends of said bar being hinged as at 32', in the form of an eye or other suitable means, to the sleeves 34' slidable on the loop 24. By adjusting the bar 30' along the length of the loop 24, the size of the opening in the loop may be adjusted. The bar 30' may, of course, be omitted, as desired.

While I have thus described my invention with great particularity, it will be clear that the same may be modified throughout a wide range. I accordingly do not propose to be limited to the exact details of construction shown and described, but reserve the right in practice to make any and all modifications thereof that fall within the scope of the appended claims.

I claim as my invention:

1. An automobile hat rack adapted to be positioned on the top of an automobile comprising a pair of anchoring devices adapted to be secured to said top, a kerfed projection extending outwardly from each of said devices, a hat bearing loop having its ends hinged to said projections, and a spring surrounding each of said projections, one end of each of said springs engaging said kerf and the other end engaging said loop.
2. An automobile hat rack including a pair of bent over anchoring devices for securing said rack to the top of an automobile, a spring supporting projection extending through a perforation in each of the bent over portions of said devices, a hat bearing loop having its ends hinged to said devices, and a spring engaging each of said projections and the ends of said loop.
3. An article holding rack adapted for special use in connection with the top of an automobile comprising a pair of anchoring plates secured to said top, a pair of projections extending from said plates, an article supporting loop hinged to said projections, a spring connected with each end of said loop and said projections, and means hinged to said loop for adjusting the opening formed by said loop so articles of different sizes may be supported.
4. In an article of the class described, a pair of inwardly turned angular supporting plates, an outwardly extending projection connected to each of said plates, a loop having its ends looped about said projections, and a pair of springs for resisting the movement of said loop, each of said springs having one end looped about one end of said loop, and its other anchored to said projections.

In testimony whereof I have signed my name to this specification.

OLIVER W. ECKSTEIN.
